United States Patent Office.

I. D. SEELEY, OF HUDSON, WISCONSIN.

Letters Patent No. 77,663, dated May 5, 1868.

IMPROVEMENT IN WASH-BOILERS.

The Schedule referred to in these Letters Patent and making part of the same.

TO ALL WHOM IT MAY CONCERN:

Be it known that I, I. D. SEELEY, of Hudson, in the county of St. Croix, and State of Wisconsin, have invented a new and useful Improvement in Boilers for Use in Cleansing Clothes; and I do hereby declare that the following is a full, clear, and exact description of the same, reference being had to the annexed drawings, making part of this specification, in which—

Figure 1 is a perspective view, and

Figure 2 is a vertical transverse section.

The same letters in both figures are used to designate the same parts.

My invention is intended to be applied to washing-boilers of the class described in M. W. Staples' patent, of February, 1867, in which the water is discharged on top of the clothes through vertical pipes leading from the bottom of the boiler, and consists in adding to such pipes, flanges, which, extending across the boiler, near the bottom, serve to promote a more rapid circulation.

I have shown in the annexed drawings one arrangement of parts. Other modifications will readily suggest themselves, but being merely equivalent modes, need not be shown in connection with this application.

A is the body of the wash-boiler, represented in the ordinary oblong form in common use in cooking-stoves. The form of the boiler is, however, immaterial. Within the boiler are chambers, formed by plates B, enclosing one or more compartments; open below, and having holes, B¹, at the top, for the escape of the water. Instead of the compartment formed, as shown, by a flat plate, a series of tubes of any form may be employed, widening gradually from the top towards the bottom, when, whether one or more compartments are formed, the plates enclosing them are connected with an inclined plate, B², extending towards the opposite side of the boiler. I have shown, in fig. 2, two of these transverse plates, B, extending from opposite sides, one over the other.

The space between two oppositely-extended plates, or between a single plate and the opposite side, must be sufficient to enable the water to flow gradually through the same, but narrow enough, in conjunction with the clothes filling the boiler above said plates, to obstruct and prevent any rapid flow of the water. To increase the obstruction, such space may be filled with sponge, or other equivalent porous substance, which will transmit the water slowly, but prevent its flowing in a rapid current.

The perforated plate C is placed in the boiler, to sustain the clothes above the plates B². The boiler being filled with water to a level a few inches above the plate C, and the clothes placed on said plate, and the heat applied to the boiler, when the water begins to boil, prevented from rising into the chamber of the boiler by the plates B² and the clothes, it will be forced upwards through the space between the plate B and the shell of the boiler and poured in a continuous stream upon the clothes, flowing downwards through the same, carrying with its current the impurities taken up from the clothes.

By this means the clothes will under ordinary conditions be cleansed without rubbing them, it being only necessary to rinse them when taken from the boiler.

My invention is distinguished from that of M. W. Staples, patented in February, 1867, and all others in which side-pipes are employed, in this, that I add to the vertical pipes and perforated plate upon which the clothes are placed this further element, viz, the inclined flanges or plates B², extending from the lower termination of the vertical tubes or compartments in near proximity to the bottom of the boiler, for the purpose of forming an obstruction to the rising current of water and diverting it through the tubes, independently of the clothes placed upon the perforated plate, which in the other boilers referred to forms the only impediment to the upward current. I do not claim the vertical pipes independently, but only in combination with the flanges B².

What I claim as my invention, and desire to secure by Letters Patent, is—

In a washing-boiler, the combination of the plates B, forming vertical compartments, the transverse and diagonally-placed plates B², forming a continuous flange in extension of said plates B; and the perforated plate C, placed above the flanges B², substantially as and for the purpose set forth.

In testimony whereof, I have signed my name to this specification in the presence of two subscribing witnesses.

I. D. SEELEY.
